UNITED STATES PATENT OFFICE.

FRANK A. POND, OF SAN DIEGO, CALIFORNIA.

DIRECTION SIGNAL.

Application filed April 8, 1924. Serial No. 705,001.

To all whom it may concern:

Be it known that I, FRANK A. POND, a citizen of the United States, residing at San Diego, in the county of San Diego and

5 State of California, have invented a new and useful Direction Signal, of which the following is a specification.

This invention relates to a direction signal designed primarily for use on motor vehicles, one of the objects of the invention being to provide a simple yet efficient device of this character which can be applied readily to a vehicle and which can be operated by a wheel or other device within convenient reach of the driver so as to move one or more designating members to selected positions, thereby indicating to nearby persons the contemplated move by the driver.

10 A further object is to provide a movable indicator carrying lights so that the position of the indicator can be determined readily at night as well as during the day.

With the foregoing and other objects in view which will appear as the description 15 proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

20 In said drawings

Figure 1 is a side elevation of the apparatus, a portion of the vehicle to which it is attached being illustrated with broken lines.

Fig. 2 is a face view of one of the indicator 25 housings.

Fig. 3 is a section on line 3—3, Fig. 2.

Fig. 4 is a detail view of the operating lever.

Referring to the figures by characters of 30 reference 1 designates a lever with which is combined a stationary arcuate rack 2, this lever being preferably mounted adjacent to and preferably parallel with the rack 2 is a guide segment 3 provided in the present instance with suitably arranged notches 4 adjacent which are appropriate designating characters such as "L," "F," "R," "S," "ST," "B," indicating respectively, "Left," "Forward," "Right," "Stop" and "Back."

35 The lever 1 is mounted to swing about a pivot 5 and has any suitable means such as a

spring pressed dog or the like, shown generally at 6 for engaging in any one of the notches 4 to hold the lever against movement.

Journalized in suitable bearings adjacent lever 1 is a shaft 7 having a gear 8 constantly in mesh with the rack 2. Thus when lever 1 is swung to the right or to the left the rack thereon will rotate gear 8 and cause a corresponding rotation of the shaft.

A bracket 9 is secured to the rear portion of the body B and has formed on or secured to it a housing 10, the rear portion of which is closed by a transparent disk 11 which can be held to the housing in any suitable manner, as by means of a ring 12. A bendable pipe 13 is secured at one end to the center of the housing and extends longitudinally of the body, this pipe terminating close to the lower bearing 17 of shaft 7. A flexible shaft 18 is mounted for rotation in the pipe 13 and has one end secured to the lower end of shaft 7 while the other end is secured to a tubular stud 19 journaled in the center of the housing 10. Formed on or secured to this stud is a movable indicator 20 which can be in the form of an arrow adapted to rotate within the housing 10. The exposed face of the arrow can be suitably colored so as to stand out prominently and electric lamps 21 can be carried by the end portions of the indicator. The wires leading to these lamps can be extended through the tubular stud 19 and thence through the tubular flexible shaft 18 to any suitable point where they can be attached to the lighting system of the vehicle.

That surface of the back of the housing 10 which is exposed through the transparent disk 11 is provided with indicating marks 22 suitably designated, as by the words "Left," "Forward," "Right," "Slow," "Stop" and "Back," these words corresponding with the designations on the segmental guide 3.

Mounted on the body of the vehicle or at one side of the wind shield, or at any suitable point at the front of the vehicle is a bracket 23 having a lamp housing 24 corresponding with the housing 10 and also provided with a movable indicator and with suitable designating characters such as illustrated in Figs. 2 and 3. A pipe 25 extends from the upper bearing 17 to the back of the housing 24 and is adapted to house a tubular flexible shaft similar to the shaft 18. Thus it will be seen that when lever 1 is shifted

- to any desired position on the guide 3, the shaft 7 will be rotated so as to impart a corresponding movement of the flexible shafts and to the movable indicators 20. Consequently these indicators will be shifted to point to the mark 22 selected by the driver and, therefore, persons back of and in front of the vehicle will be apprised of the next contemplated move of the driver.
- 10 It is to be understood that any desired coloring can be used on the movable indicators and the lamps carried thereby can be suitably colored as shown in Figs. 2 and 3 wherein the parts are lined for color.
- 15 What is claimed is:—

The combination with a vehicle and front and rear housings carried thereby, of a movable indicator within each housing, flexible shafts connected to and rotatable with the

indicators, lamps carried by the indicators, 20 said flexible shafts constituting conduits, wires housed within the flexible shafts or conduits for conducting electric current to the lamps on the indicators, a shaft connected to and rotatable with the flexible 25 shafts, a gear thereon, an actuating lever, a rack carried by the lever and meshing with the gear, and means cooperating with the lever for indicating the positions of the indicators within the respective housings. 30

In testimony that I claim the foregoing as my own, I have hereto affixed my signature in the presence of two witnesses.

FRANK A. POND.
